Primary Examiner — Sharon S Oum(74) *Attorney, Agent, or Firm* — Carlson, Gaskey & Olds, P.C.(57) **CLAIM**

The ornamental design for a leading edge of a fan blade, as shown and described.

DESCRIPTION

FIG. 1 is a perspective view of a leading edge of a fan blade, shown in its environment;

FIG. 2 is a front view of the leading edge of the fan blade of FIG. 1;

FIG. 3 is a front perspective view of the leading edge of the fan blade of FIG. 1;

FIG. 4 is another front perspective view of the leading edge of the fan blade of FIG. 1;

FIG. 5 is a first side view of the leading edge of the fan blade of FIG. 1; and,

FIG. 6 is a second side view of the leading edge of the fan blade of FIG. 1.

The dash-dash broken lines illustrate portions of the leading edge of the fan blade and environment. The dash-dot broken lines define the bounds of the claimed design. None of the broken lines form part of the claimed design.
